COMBINATION SKIRT AND PANTY

David H. Millman, New York, N. Y.

Substitute for abandoned application Serial No.

558,497, October 13, 1944. This application

March 6, 1947, Serial No. 732,739

2 Claims. (Cl. 2—221)

1

This invention relates to new and useful improvements in a combination skirt and panty.

This is a substitute for my previous abandoned application, filed on October 13, 1944, Serial No. 558,497.

More specifically, the invention proposed the construction of a combination skirt and panty characterized by a skirt body having an invisible crotch portion and which is adapted to be used in playsuits, bathing suits, skirts and other similar garments worn by girls and women.

More specifically, the invention proposed the construction of a combination skirt and panty characterized by a cloth tubular member forming a skirt-like body and having cloth panels mounted on the front wall and on the back wall thereof forming double layer portions in these areas to shadow proof the same.

Still another object of the invention proposes forming a crotch between the inner layers of the double layer portions of the combination skirt and panty in a manner to hold the bottom portion of the garment in a position in which it will cling to the contour of the body.

Still another object of the invention proposes the formation of pleats at the point of connection between the side edges of the panels with the skirt-like body in a manner to provide the bottom thereof with expanding portions, permitting free leg movement.

Still another object of the invention proposes cutting flap portions from the abdomen areas and the inner layers of the double layer portions and which may be extended against the abdomen or about the sides of the body and which are adapted to be connected together by means of laces passing through aligned openings formed in the adjacent free edges of the flap portions.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a front elevational view of a combination skirt and panty constructed in accordance with this invention.

Fig. 2 is a bottom plan view of Fig. 1.

Fig. 3 is an enlarged partial horizontal sectional view taken on the line 3—3 of Fig. 1.

Fig. 4 is an enlarged partial vertical sectional view taken on the line 4—4 of Fig. 1.

2

Fig. 5 is a view similar to Fig. 3 but illustrating a modification of the invention.

Fig. 6 is a view similar to Fig. 1 but illustrating a still further modification of the invention.

Fig. 7 is a horizontal sectional view taken on the line 7—7 of Fig. 6.

Fig. 8 is a partial vertical sectional view taken on the line 8—8 of Fig. 7.

Fig. 9 is a view similar to Fig. 6 but illustrating an adjusted position of the panels.

Fig. 10 is a partial horizontal sectional view taken on the line 10—10 of Fig. 9.

Fig. 11 is a view similar to Fig. 7 but illustrating another form the invention.

15 The combination skirt and panty, according to this invention, includes a cloth tubular member 10 forming a skirt-like body and which has cloth panels 11 mounted on the front wall and the back wall thereof. These cloth panels 11 are extended externally of the skirt-like body and have their edges secured to the adjacent faces of the skirt-like body by means of stitches 12. A crotch 13 is fashioned between the inner layers of the double layer portions formed by engaging the panels 11 upon the front and back walls of the skirt-like body. The crotch portion 13 is of conventional construction and is provided for causing the bottom portion of the garment to cling to the contour of the body.

20 Pleats 14 are formed at the point of connection between the side edges of the panels 11 with the skirt-like body 10. The pleats 14 in this first form of the invention have portions 14^a formed in the skirt-like body 10 and opposed portions 14^b formed in the adjacent side edges of the panels 11. The top portions of the pleats 14 from the waist area partially downwards along the front and back thereof are maintained in a closed position by means of vertical lines of stitches 15.

25 A waist engaging band 16 is mounted along the top edges of the skirt-like body 10 and the panels 11 and is secured in position by means of a line of stitches 17.

30 In the modification of the invention shown in Fig. 5 the panels 11' are projected along the inside faces of the front and back walls of the cloth tubular member 10 which forms the skirt-like body. The crotch 13' in this form of the invention is formed between the panel portions 11' while the pleats 14' are formed entirely in the skirt-like body formed by the cloth tubular member 10. In other respects this form of the invention is similar to that previously shown and like reference numerals identify like parts in each of the several views.

In the modification of the invention shown in Figs. 6-10 the construction of the combination skirt and panty is similar to that shown in Figs. 1-4, except for the abdominal areas of the inner layers of the double layer portions which are formed by engaging the panels 11 in position over the front and back walls of the skirt-like body 10. In this form of the invention the abdominal areas of the garment are provided with laterally extending flap portions 20 which are cut from the double layer of material and which are adapted to be extended across the abdominal area of the garment, as shown in Figs. 6 and 7, or to the sides of the garment, as shown in Figs. 9 and 10. The adjacent free edges of these flaps 20 are provided with aligned openings 21 through which a lace 22 is adapted to be engaged for connecting these free edges of the flap portions together. Thus the flap portion 20 may be drawn together to apply pressure to the abdomen portions of the body or to the hip areas, depending upon the direction in which these flap portions are projected. In other respects this form of the invention is similar to that previously shown and like reference numerals identify like parts in each of the several views.

In Fig. 11 each pleat 14" is formed by folding the panel portion 11" at its ends 11^a and thereafter stitching the same to the tubular member 10 and to an inner panel 11^c by stitches 12".

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a garment having a tubular body formed at the bottom with a crotch portion and panels extended along the front and back of the body forming double layers of material at the front and back between the top of the body and the top of the crotch, a pair of front flaps cut from the material of the body at the front thereof in the area of double layer material, a pair of rear

10
15

flaps cut from the material of the body at the back thereof in the area of double layer material, said flaps being on a common plane and integral with the body at the outer edges thereof so that the pairs of flaps may be extended with their free edges facing each other or extended along the inner sides of the body with the free edges of the front flaps facing the free edges of the rear flaps, and means for releasably connecting together the free edges of said flaps in either of their two positions.

2. In a garment having a tubular body formed at its bottom with a crotch portion and panels extended along the front and back of the body forming double layers of material at the front and back between the top of the body and the top of the crotch, a pair of front flaps cut from the material of the body at the front thereof in the area of double layer material, a pair of rear flaps cut from the material of the body at the back thereof in the area of double layer material, said flaps being on a common plane and integral with the body at the outer edges thereof so that the pairs of flaps may be extended with their free edges facing each other or extended along the inner sides of the body with the free edges of the front flaps facing the free edges of the rear flaps, and means for releasably connecting together the free edges of said flaps in either of their two positions, said releasable connecting means comprising laces extended between horizontally aligned pairs of openings formed in the free edges of said flaps.

DAVID H. MILLMAN.
